C. FRAIR.
WORK HOLDING STAND.
APPLICATION FILED MAR. 10, 1920.

1,398,096.

Patented Nov. 22, 1921.

UNITED STATES PATENT OFFICE.

CHESTER FRAIR, OF SEATTLE, WASHINGTON.

WORK-HOLDING STAND.

1,398,096.

Specification of Letters Patent. Patented Nov. 22, 1921.

Application filed March 10, 1920. Serial No. 364,709.

To all whom it may concern:

Be it known that I, CHESTER FRAIR, a citizen of the United States, residing at Seattle, in the county of King and State of Washington, have invented certain new and useful Improvements in Work-Holding Stands, of which the following is a specification.

This invention relates to stands which are designed, more especially, for reversibly holding automobile engines or the like while being operated upon in a shop. The object of my invention is the provision of a device of this character which will be of inexpensive, strong and durable construction, and which is adapted to be readily adjusted to accommodate various sizes of engines, and is convenient in use.

The invention consists in the novel construction, arrangement and combination of parts as will be hereinafter described and claimed.

In the accompanying drawings, Figure 1 is a side elevational view of a stand embodying my invention shown applied.

Fig. 2 is an end elevation of the same with the work and bracket supports therefor in positions reversed from where they are represented in Fig. 1.

Fig. 3 is a horizontal section through 3—3 of Fig. 1.

Fig. 4 is a detail transverse sectional view of one of the bracket connections with a side member of the stand.

Fig. 5 is a sectional view taken substantially through 5—5 of Fig. 2, with parts broken away.

Fig. 6 is a perspective view of a rail attachment for a stand bracket.

Fig. 7 is a fragmentary elevational view of one of the side members of the stand.

According to the present invention I provide a stand having two complementary frames 10 and 10¹ each of substantially the shape of an isosceles triangle formed of sheet steel to provide a central web portion 11 and marginal flanges 12 at the sides and extending over the upper angle.

To each of the lower corners of the frame is secured as by rivets 13 the flange element 14 of a chambered casting 15 through which extends an axle 16 for a ground wheel or roller 17.

Extending transversely through the frame webs and the respective flanges 14 are parallel bars, such as pipes 18, which are rigidly secured to the frame 10 by nuts 19 en-

gaging pipe threads at opposite sides of the frame as shown in Figs. 3 and 5. The pipes 18 are adjustably connected to the other frame 10¹ by slidably fitting in bosses or sleeve elements 20 of the respective castings and secured by set-screws 20 for retaining the frames at selected distances apart.

Rigidly secured within the spaces afforded by the frame flanges 12 at the upper angle 65 of the respective frames are apertured blocks, as 22 serving as bearing boxes for screw bolts 23 and 23¹ which support hanger blocks 24 and 24¹, one to the inner side of each frame. The hanger block 24 is provided with tongues or projections 25 (Fig. 4) adapted to engage in slots 26 extending radially from the bolt receiving aperture 27 of the adjacent bearing block 22 (Fig. 7) for retaining the hanger blocks in rotary 75 adjustments.

Such engagement of the said tongues and grooves are effected by means of the bolt 23 and nut 28. This bolt 23 is prevented from turning by socketing its polygonal head 23² 80 in a correspondingly shaped recess 24² provided in the associated block 22. The nut 28 for bolt 23 is desirably provided with a lever handle 28¹ to facilitate the turning of the same. The nut 29 for the other bolt 23¹ 85 may also be provided with a similar handle, or as shown, be of ordinary construction to be tightened or loosened through the medium of a suitable wrench.

30 represent angle bars secured to the 90 lower ends (Fig. 2) of the hanger blocks 24 and 24¹ by bolts 31 passing through holes 32 provided on the bar flanges 30¹. The other bar flanges are desirably formed with longitudinal slots 33 to accommodate bolts 95 34 for clamping plates 35 between which and the adjacent bar flanges 30² the flanges as A of an engine block B may be secured.

For operation, the stand is wheeled on its rollers 17 to the place whereat an engine 100 block at B is to be received and which block is placed upon the bars 30 when the hanger blocks 24—24¹ are pendent as shown in Fig. 2.

The work thus supported upon bars 30 is 105 then secured thereto with its flanges A below the clamping plates 35 by means of bolts 34.

Any operations to be done upon the work, such as grinding valve seats, etc., which may 110 be most conveniently performed with the work upright is accomplished with the

work and supporting parts therefor in the positions in which they are illustrated in Fig. 2.

When the work is to be operated upon from the sides or bottom it may be brought into inclined or reversed positions, as indicated in Figs. 1 and 4, by rotatably moving the same about the axes of bolts 23 and 23¹ and secured in selected positions by utilizing the respective nuts 28 and 29. The width or space between the work supporting bars 30 is regulated to correspond with the widths of various engine blocks by regulating the position of the frame 10 with respect to the frame 10¹ by first loosening set screws 21 and then moving the frame 10¹ longitudinally of the pipes 18 and, finally, securing the frame 10¹ to said pipes by means of the set screws.

The operation and advantages of the invention will be understood from the foregoing description.

What I claim, is—

A work-holding stand of the character described comprising, in combination, a pair

of frames, a pair of bars extending through the lower portions of said frames, means for securing said bars to the frames to retain the latter in different positions of adjustment; apertured bearing blocks rigid with the upper ends of said frames, one of said blocks being provided with recesses disposed radially of the block aperture, work-supporting blocks, means for securing work thereto, bolts extending through apertures of the bearing blocks and the supporting blocks for pivotally connecting the supporting blocks to the respective frames, and a tongue provided on one of said supporting blocks and engaging in selected of the aforesaid recesses for retaining the respective supporting block in various predetermined rotary positions.

Signed at Seattle, Washington, this 4th day of March, 1920.

CHESTER FRAIR.
